ENGINE STARTING MECHANISM

Charles Raymond Waseige, Rueil-Malmaison, France, assignor to Société Air Equipment, Billancourt, Seine, France, a company of France

Original application June 29, 1935, Serial No. 29,162. Divided and this application February 9, 1939, Serial No. 255,526. In France July 24, 1934

3 Claims. (Cl. 123—179)

This invention relates to engine starting mechanism and more particularly, though not exclusively, to starting apparatus of the inertia type.

In so far as the present invention relates to apparatus for the starting of the engines by inertia, it has for an object the improvement of these devices. To this end, and this constitutes one of the characteristics of the present invention, the organ that couples the inertia element to the engine to be started is automatically controlled so as to effect the coupling at the moment desired through the intermediary of a quick release mechanism actuated either by a centrifugal regulator or by a progressive advance mechanism which operates as a function of the number of turns effected by the flywheel or the starting motor.

Another object is to provide automatic ignition interrupting means or mechanism controlling automatically the throttle of the starting motor in order that, after the starting of the engine, the starting motor may be automatically brought to idling speed. In the case envisaged the starting motor continues to rotate slowly with just sufficient energy to overcome the cylinder compression, and is then stopped automatically and completely when the engine has effectively started and when it is determined that it will be no longer necessary to re-energize the flywheel.

Another object is to provide means facilitating turning by hand of the engine engaging member in a sense inverse to that communicated to it by the starting motor.

In one embodiment for the realization of this end, utilization is made of a three-position crank for the rotation of the starting motor, the crank permitting the rotation thereof in either direction.

For the purpose of a clearer understanding of the subject matter of the present invention, reference is to be had to the accompanying drawings, wherein:

Figure 1 is a view in elevation of the starting mechanism;

Figure 2 shows an automatic control for the clutch that is adapted to connect the starting motor to the engine to be started when the former has effected a predetermined number of turns.

Figure 3 is a change speed mechanism between the starting motor and the flywheel.

Figure 4 is a plan view in large scale of a device for the starting of the starting motor.

1 indicates, in Fig. 1, the crankshaft of the engine to be started; 2, the inertia element of the 55

starter; 3, the reduction gear train; and 4, a screw pinion carried by a screw 5 that is freely mounted on an axis of the gear train, but drivably connectable to said axis by engagement of dog clutch 6. Such engagement is under the control of a link-rod 8 and a shifter yoke straddling the neck 7 of the slideable (driving) element of the dog clutch.

The flywheel accelerating engine 9 (the "starting motor") is shown as provided with a starting crank 14, and is carried directly by the housing 10 of the starter, said housing being in turn carried on the main engine housing or crank-case 11. Upon acceleration to a predetermined speed, a gear train driven governor 17 will bring about actuation of link-rod 8, the control therebetween being in the form of a bell-crank 15 providing a sudden, snap-action shift of clutch 7, 6 as soon as a rod 16 assumes a predetermined position to 10 which it is moved by the governor, against the yielding opposition of a spring 18. This rod 16 also operates a second rapid release bell-crank 19 engageable with a shoulder 20 of a rod 13 to produce a rapid disengagement of a clutch 12 drivably connecting engine 9 to the gear train 3; the spacing of the parts being such that this disengagement of clutch 12 occurs simultaneously with, or slightly after, engagement of clutch 7, 6. Rod 13 carries a second shoulder 13a which cooperates with a bell-crank 21 and connections 21a and 21b leading to the throttle of engine 9, for the purpose of automatically shifting said throttle to idling position simultaneously with the disengagement of the clutch 12 by the means previously described; the connection to the throttle being such that the manual operation thereof by the means shown at 24 remains effective whenever desired, and independently of the rod 21a. In addition to this automatic shifting of the 20 throttle to idling position there is provided means automatically shifting the throttle to the fully closed position, said means being shown as including the linkage 23 acting upon the throttle rod 24 to close the throttle automatically in response to movement of the screw pinion 4 in the direction of the arrow f, such movement occurring automatically when the main engine has been effectively started.

If the engine does not start, the rod 16 returns 30 to its original position under the action of the spring 18 according as the element which effects rotation of the regulator 17 slows down. Through the effect of this return movement of the rod 16 the device 15 swings suddenly at a given moment in the direction opposite to the arrow f₂ and per-

mits the spring of the pull member 8 to interrupt the connection between the nut 7 and the screw 5. The mechanism now lends itself to a new starting attempt, but as the screw pinion 4 has remained in gear with the engine to be started, any failure of the gearing elements to slip with sufficient freedom might cause a breaking of gear teeth. As a further, although not absolutely rigid and unyielding safeguard against such breakage, a blocking of the control mechanism of the coupling 12 is provided, to yieldably oppose the engagement of the coupling as long as the screw pinion 4 is engaged with the motor to be started.

For this purpose there is provided a swinging lever 24a the extremity of which in the form of a fork engages with a trunnion of the rod 23. Coaxially to the lever 24a is mounted another lever 24b drawn toward lever 24a by a spring 24c. The arrangement is such that when the rod 23 is in the position for which the pinion 4 is disengaged, the extremity of the lever 24b is not situated on the trajectory of a shoulder 24d of the rod 13, but for the position that the rod 23 occupies when the pinion 4 is engaged, the said extremity of the lever 24b comes into position on this trajectory between the positions of the shoulder 24d corresponding to the engagement and to the disengagement of the coupling 12. Furthermore, the trajectory of the extremity of the lever 24b does not encounter the shoulder 24d for the position of disengagement of the rod 13. It results therefore, as in the position indicated in Fig. 1, that the lever 24b opposes itself to the engagement of the coupling 12, but before this occurs the rod 13 is allowed to come back to its position corresponding to disengagement against the effort of the spring 24c and as a result of the push of the shoulder 24d in the course of the disengagement of the coupling 12.

For the purpose of absolutely disengaging the screw pinion 4 recourse may be had to a three-position crank (Fig. 4) for the starting of the motor 9, one neutral position being provided and two other positions permitting the motor to be turned in opposite directions. The hand crank 14 carries on its opposite faces the teeth 30 and 31 cooperating respectively with two other teeth 32-33 fixed to or forming part of the motor shaft, the hand crank being normally maintained in its medium neutral position by the opposed springs 34-35. All that is necessary to disengage the pinion 4 and permit a new attempt of starting is to turn the engine in its non-normal sense.

For the purpose of permitting the rotation at will and by hand of the engine to be started in utilizing the hand crank 14, there is here provided a link 15a articulated on a lever 15b angularly fixed with respect to levers 15c and 15d of the quick release device 15 which controls the clutching of the engine to be started to the inertia flywheel. This clutch can be thus controlled at will and by hand independently of the automatic control provided therefor.

Figure 2 shows another form of embodiment of automatic control of the rod 16 in function of the number of turns effected by the starting motor 9 or of the flywheel 2. In this embodiment the shaft of the starting motor 9 or the transmission to the flywheel motivates, through the intermediary of a reduction gearing 25, here illustrated as of the worm type, a threaded shaft 26 that is axially fixed and along which may

displace a half screw 27 guided in such a way that it cannot turn. Two trunnions carried by this screw 27 are engaged by a fork 28 provided at the extremity of one arm of a two-armed lever of which the other arm is articulated on the rod 16. It will be understood that at the end of a definite or determined number of turns the rod 16 comes into the position for which take place automatically the operations hereinabove set forth for the control by the centrifugal regulator.

The guide bar 36 of the screw 27 is carried at its extremity by two levers 37 that are arranged to pivot about the same axis in order to permit the disengagement of the screw 27 from the threaded shaft 26 and a spring 38 is provided which continually urges the screw 27 in the sense contrary to the displacement which results from the action of the motor 9 thereon. It is obvious that when the connection between the screw 27 and the threaded shaft 26 is interrupted by the raising of the screw, the latter is returned along the bar 36 by the spring 38 and comes back into its initial position bringing with it the rod 16 through the intermediary of the lever 29. The raising of the screw 27 is obtained in this embodiment through any desired mechanism as for instance through the intermediary of a Bowden cable, but it is to be understood that the operation may be effected by any other mechanism adapted to the conditions imposed.

Referring to Figure 3, there is provided an embodiment of an automatic change speed disposed between the starting motor and the flywheel. In this embodiment a planetary gear train is utilized of which one of the planetaries 40 is connected to rotate with the flywheel 2 while the other planetary 41 may be immobilized or connected for rotation to the shaft 42 of the starting motor 9 through the intermediary, for example, of a jaw clutch of which one of the jaws is displaceable and splined to the tail of the planetary 41. The movable jaw carries two opposite teeth 43 and 44 adapted to be brought respectively into engagement with two teeth 45 and 46, the one 45 fixed to the housing and the other 46 carried by a plate of the shaft 42. The satellites 47 are always set in motion directly by the shaft 42 of the starting motor.

The engagement in one sense or in the other is controlled by a quick release device 48 that is actuated automatically by a cam 50 motivated by the mechanism which controls the rod 16. In the embodiment represented this cam 50 is carried by the rod 16. It is obvious that when teeth 43 and 45 are in engagement, the shaft of the flywheel is rotated with a certain reduction by the shaft 42 whilst, when the teeth 44 and 46 are in engagement, a direct coupling between the shaft 42 and the flywheel 2 results. The first position corresponds to the getting under way of the motor 9 and of the flywheel 2. Then, when the flywheel and the motor have acquired a certain predetermined speed or effected a number of turns chosen in advance, the cam 50 actuates the mechanism 48 which releases and brings into engagement the teeth 44 and 46 effecting thus the direct connection between the driving shaft and the driven shaft.

This application is a division of my application No. 29,162 filed June 29, 1935.

What I claim is:

1. A starting mechanism for aircraft engines comprising starting power means, a flywheel, an

engine engaging member, means drivably connecting the flywheel to said engine engaging member, means including a clutch to drivably connect the starting power means to the flywheel, and automatic means for disengaging said clutch after the starting power means has operated through a predetermined number of revolutions, said automatic means comprising a member shiftable to clutch disengaging position, and means driven by the rotation of said power means for shifting said shiftable member.

2. A starting mechanism for aircraft engines comprising starting power means, a flywheel, an engine engaging member, means drivably connecting the flywheel to said engine engaging member, means including a clutch to drivably connect the starting power means to the flywheel,

5 automatic means for disengaging said clutch after the starting power means has operated through a predetermined number of revolutions, said last named means including a screw element movable along a threaded shaft, means for guiding said screw element in such a way as to prevent rotation thereof, and means for driving said threaded shaft in synchronism with said flywheel.

10 3. A starting mechanism for aircraft engines, as in claim 1, wherein the starting power means includes an internal combustion engine, and further comprising means acting upon the throttle of said starting engine to slow down and subsequently stop said starting engine at predetermined stages in the operation of the starting mechanism.
